UNITED STATES PATENT OFFICE

98,884

DESIGN FOR A BOX

Charles M. O'Brien, San Jose, Calif.

Application August 5, 1935, Serial No. 57,972

Term of patent 7 years

To all whom it may concern:

Be it known that I, Charles M. O'Brien, a citizen of the United States, residing in the city of San Jose, county of Santa Clara, and State of California, have invented a new, original, and ornamental Design for a Box, of which the following is a specification, reference being had to the accompanying drawings, forming a part thereof.

In the accompanying drawings:

Fig. 1 is a top plan view of a box, illustrating my new design.

Fig. 2 is a side view of the same.

I claim:

The ornamental design for a box as shown.

CHARLES M. O'BRIEN.
